G. L. McARTHUR,
HURL SIZER AND SHAKER.
APPLICATION FILED AUG. 30, 1919.

1,384,475.

Patented July 12, 1921.

UNITED STATES PATENT OFFICE.

GEORGE L. McARTHUR, OF RACINE, WISCONSIN.

HURL SIZER AND SHAKER.

1,384,475.

Specification of Letters Patent. Patented July 12, 1921.

Application filed August 30, 1919. Serial No. 320,816.

To all whom it may concern:

Be it known that I, GEORGE L. McARTHUR, a citizen of the United States, and resident of Racine, in the county of Racine and State 5 of Wisconsin, have invented new and useful Improvements in Hurl Sizers and Shakers, of which the following is a description, reference being had to the accompanying drawings, which are a part of this specification.

10 The present invention relates to certain new and useful improvements in hurl sizers and shakers employed in the manufacture of brooms.

One object of the present invention is to 15 provide a machine of the class described which will have means for engaging and clamping therebetween the ends of the longer straws of a bundle of straws being sized and having means for reciprocating the 20 same to disengage the shorter straws from the bundle.

Another object of the present invention is to provide two series of finger members or 25 tines movable to engage in a bundle of straws to be sized in interlocked position and then movable to clamp the straws therebetween whereby the same may be reciprocated to disengage the shorter straws therefrom.

A further object of the present invention 30 is to provide a machine of the class described employing finger members or tines connected together by lazy tongs to retain the finger members or tines of each series in the proper spaced relation with reference to each other.

35 A still further object of the present invention is to provide a machine of the class described including a main frame having a table reciprocally mounted therein for receiving a straw container and having lazy 40 tong means for moving the same to various adjusted positions in the main frame.

With the above and other objects in view which will appear as the description proceeds, my invention resides in the novel construction, combination and arrangement of parts substantially as hereinafter described and more particularly defined by the appended claims, it being understood that such changes in the precise embodiment of the 45 hereindisclosed invention may be made as come within the scope of the claims.

In the accompanying drawing I have illustrated one complete example of the physical

embodiment of my invention constructed according to the best mode I have so far devised for the practical application of the principles thereof, and in which:

Figure 1 is a view taken through a machine embodying the various features of my invention, parts being broken away and in section to more clearly illustrate the various details of construction.

Fig. 2 is a view taken through my machine at right angles with respect to the view illustrated in Fig. 1, parts being broken away and in section to more clearly illustrate details of construction.

Fig. 3 is a top plan view of the two sets or series of finger members or tines illustrating the same as in disengaged position, the hanger members for supporting the same being removed.

Fig. 4 is an enlarged sectional view taken transversely through the lower ends of two of the finger member supporting hangers,

75 Fig. 5 is a detail fragmental view of the means for releasably locking the finger members or tines in clamping position.

Referring now more particularly to the accompanying drawing, 6 designates a main frame in which is vertically slidably mounted a supplemental frame 7 suspended from the top of the main frame by spring hangers 8. Also vertically slidably mounted in the main frame independent of the supplemental frame 7 is a table or platform 9 for supporting a container or receptacle 10, to be later described. Lazy tongs 11 have the upper ends of the uppermost links thereof pivotally connected to the table 9, as at 12, and have one of the lowermost links extended, as at 13, beyond the other lowermost link thereof, and pivoted to the supplemental frame 7, as at 14, an operating lever 15 for vertically adjusting the position of the table 9 being connected with the extended portion 13 of the lowermost link by a rod or lever 16 and being pivotally connected to a quadrant or rack member 17 secured to the supplemental frame.

As best shown in Fig. 1, the quadrant or rack member 17 has suitable teeth formed on its periphery for retaining the lever 15 in adjusted position, and an upward movement 105 of the lever 15 will extend the lazy tongs 11.

- and thus raise or lower the table 9, and a movement of the lever 15 in a reversed direction will lower the table 9. The straws, as indicated at 18, to be sized are positioned in 5 the container 10, and as they are relatively loose the lower ends of the straws will engage the bottom of the container and thus position the upper ends of the longer straws above the upper ends of the shorter straws.
- 10 After the straws have been so positioned, the upper ends of the longer straws are clamped between finger members or tines 19 and the table 9, with the container 10, is dropped and the finger members or tines reciprocated 15 by means of the supplemental frame 7 to disengage or shake the shorter straws, not clamped by the finger members or tines 19, from the bundle to fall back into the container 10.
- 19 Fixed to the upper end of the supplemental frame 7 is a horizontal rack or frame 20 having guide grooves 21 on the inner face of its sides for slidably mounting therein a pair of guide frames or members 22, from which 25 the finger members or tines 19 are suspended. The members 22 are movable toward and away from each other in the frame 21 by means of a wheel or pulley 23 rotatably secured to the member 21 medially of 30 its ends and having trained there around suitable chains or cables 24 and 25 trained about guide pulleys 26 disposed at the outer ends of the frame 20. As best shown in Fig. 1, the chain or cable 24 is connected to 35 the outer upper end of one of the members 22, as at 27, and the chain or cable 25 is connected to the lower outer end of the other member 22, as at 28, so that upon the rotation of the wheel 23 in one direction the 40 members 22 will be moved away from each other toward the outer ends of the frame 20, and upon rotation in a reversed direction the members 22 will be moved toward each other and toward the center of the frame 20.
- 45 The finger members or tines 19 are angular in transverse cross section and arranged to be nested when moved to engage adjacent finger members, and said finger members are arranged in two series, one series supported 50 from each member 22. Each finger member or tine 19 has secured thereto the lower ends 29 of an X-shaped hanger 30 having the upper ends of the upper arms engaged about the transverse rod 31 which has its ends 55 slidably mounted in guide grooves 32 formed in the sides of the members 22, to thus transversely movably support the finger members or tines 19 from the members 22.
- 60 The lower arms of the bracket members 30 of each series are connected together by guide rods 33 to insure the even or smooth movement of the same and prevent the rods 31 from becoming twisted in the frame 22.
- 65 To always maintain the finger members of each series in even spaced relation, the

finger members are connected together by means of a pair of lazy tongs 34 each pair having one end pivotally connected, as at 35, to a side bar 36 of each series and their outer ends pivotally connected, as at 37, to the innermost finger member or tine of each series. As best shown in Fig. 3, the side bars 36 are so arranged that when the finger members of each series are telescoped or interlocked, said side bars will be opposed to each other. The hanger members 30 each have secured thereto medially of its ends a spring member 38 which abuts against the adjacent hanger 30 to thus normally urge the hanger members 30 with the finger 80 members 19 to spaced position and means are provided for releasably locking or retaining the hanger members against movement under action of the springs 38, as will be later described.

85 When the straws 18 have been positioned as hereinabove described with the upper ends of the longer straws above the upper ends of the shorter straws, the wheel 23 is rotated to move the members 22 toward the center of 90 the main frame to interlock or telescope the finger members 19 to engage therebetween the upper ends of the longer straws. When the finger members or tines 19 are telescoped engaging therebetween the upper ends of 95 the longer straws, a treadle member 39 is depressed which engages the upper ends 40 of a pair of bell crank levers 41 pivotally carried by the main frame with the side bars 36 of the series of finger members, thus urging the finger members of one series to engage against the adjacent finger members of the other series and thus firmly clamp the straws disposed therebetween. The finger means are thus retained in clamping position by means of a latch bar 42, pivotally carried by each side bar 36 and having a toothed outer end 43 adapted to releasably engage a keeper 44 fixed to the other side bar of each series whereby pressure from the 110 treadle 39 may be relieved and the finger members still retained in clamping position.

When the finger members are thus held in clamping engagement and the ends 40 of the bell crank levers 41 disengaged from the 115 side bars 36, the supplemental frame 7 is manually reciprocated to shake loose or disengage from the bundle of straws 18 the shorter straws not engaged by the finger members 19, which shorter straws fall back 120 into the container 10 and thus readily separate from the longer straws. The bell crank levers 41 are connected with the treadle 39 by means of toggle links 45 having their outer ends pivoted to the lower ends 125 of the bell crank levers 41 and their inner ends connected to a cross head or block 46 which is connected to the treadle 39 by means of a link 47. The cross head 46 is normally urged upwardly by means of a 130

spring 48 so that the upper ends 40 of the cross head will be normally urged to an inoperative position.

What I claim as my invention is:

- 5 1. A device of the class described including finger members movable to engage in straws to be sized and then movable to clamp the straws therebetween, and means for shaking the fingers after being moved to 10 clamping position.
2. A sizing device comprising a main frame, a plurality of finger members arranged in parallel relation and mounted therein for movement longitudinally and 15 transversely, means for moving the finger members longitudinally to engage in the material to be sized, and means for moving the finger members transversely toward each other to clamp the material therebetween.
- 20 3. A straw sizer of the class described comprising a main frame, a supplemental frame reciprocally mounted in the main frame, two series of finger members supported from the supplemental frame and movable toward and away from each other to engage in a bundle of straws to be sized, means for moving the finger members of one series to engage against the adjacent finger members of the other series whereby 25 to clamp the straws therebetween, and means for reciprocating the supplemental frame to disengage the straws from the bundle not clamped by the finger members.
4. A device of the class described including finger members movable to engage in straws to be sized and then movable to clamp the straws therebetween, and treadle means for moving the finger members to clamping position.
- 35 5. A device of the class described including finger members movable to engage in straws to be sized and then movable to clamp the straws therebetween, treadle means for moving the finger members to 40 clamping position, and means independent of said treadle means for releasably locking the finger members in clamping position upon the action of said treadle means.
6. A straw sizer of the class described 45 comprising a main frame, a supplemental frame resiliently supported from the main frame and capable of vertical reciprocation, and finger members carried by the supplemental frame and movable to engage and 50 clamp straws to be sized therebetween.
7. A straw sizer of the class described comprising a main frame, a supplemental
- frame vertically reciprocally mounted therein, a pair of guide members carried by the supplemental frame and movable longitudinally in opposite directions, a series of finger members supported from each of said guide members, means for moving said guide members toward each other to interlock the finger members in straws to be sized, and means for moving the finger members to clamp the straws therebetween. 60
8. A straw sizer of the class described including two series of finger members movable to interlocking position, and lazy tongs connecting the finger members of each series. 65
9. A device of the class described, comprising a series of connected together finger members arranged in spaced parallel relation and movable to engage in material to be sized, and means for moving said finger members together after being engaged in the material to clamp the same therebetween. 70
10. A device of the class described, comprising a series of connected together finger members arranged in spaced parallel relation and movable to engage in material to be sized, means normally yieldingly retaining said finger members in their spaced relation, and means for moving said finger members together against the action of said first mentioned means after being engaged in the material to clamp the same therebetween. 75
11. A device of the class described, comprising two sets of finger members, means normally maintaining the finger members of each set in spaced relation, means for moving said sets toward each other to overlap the finger members of the sets, and means for moving said finger members side- 80
- wise to engage the finger members of one set with the adjacent ones of the other set. 90
12. A device of the class described, comprising a receptacle for receiving materials of various lengths to be sized, finger members positioned above said receptacle, means for engaging said finger members with the upper ends of the longer of said materials, means for moving said receptacle and finger members apart after said finger members have been engaged with the longer materials, and means for reciprocating the finger members to disengage the materials not held thereby from the aggregate. 95
- 100
- 105
- 110

In testimony whereof, I affix my signature.

GEORGE L. McARTHUR.
